(57) **CLAIM**

The ornamental design for an electrical plug, as shown and described.

DESCRIPTION

FIG. 1 is a right, rear, bottom perspective view of an electrical plug showing our new design;
FIG. 2 is a left, front, top perspective view thereof;
FIG. 3 is a rear elevational view thereof;
FIG. 4 is a front elevational view thereof;
FIG. 5 is a right side elevational view thereof;
FIG. 6 is a left side elevational view thereof;
FIG. 7 is a top plan view thereof;
FIG. 8 is a bottom plan view thereof; and,
FIG. 9 is an enlarged view of circled portion IX in FIG. 8. The dash-dot line shown in FIGS. 8-9 is for the purpose of illustrating the boundaries of the enlarged fragment shown in FIG. 9, and forms no part of the claimed design.
